UNITED STATES PATENT OFFICE

102,918

DESIGN FOR A CLOCK CASE

John P. Rainbault, New York, N. Y., assignor to
General Electric Company, a corporation of
New York

Application August 8, 1936, Serial No. 64,305

Term of patent 14 years

To all whom it may concern:

Be it known that I, John P. Rainbault, a citizen of the United States, residing at New York, in the county of New York, State of New York, have invented a new, original, and ornamental Design for a Clock Case, of which the following is a specification, reference being had to the accompanying drawing forming a part thereof.

Fig. 1 is a front view of a clock case showing my new design; Fig. 2 is a side view thereof; and Fig. 3 is a top plan view thereof.

The top, bottom, and central front portions of my clock case are flat surfaces and are set off from each other and from the rounded end portion of the case by distinct sharp lines or corners. The central vertical front panel projects forward, as shown, and thus appears to stand out noticeably.

I claim:

The ornamental design for a clock case as shown and described.

JOHN P. RAINBAULT.
